Primary Examiner — Susan E Krakower(74) *Attorney, Agent, or Firm* — McCarter & English LLP(57) **CLAIM**

The ornamental design for a bottle with nipple, as shown and described.

DESCRIPTION

FIG. 1 is a perspective view of a bottle with nipple;

FIG. 2 is a left side elevational view of the bottle with nipple of FIG. 1;

FIG. 3 is a right side elevational view of the bottle with nipple of FIG. 1;

FIG. 4 is a rear side elevational view of the bottle with nipple of FIG. 1;

FIG. 5 is a front side elevational view of the bottle with nipple of FIG. 1;

FIG. 6 is a top plan view of the bottle with nipple of FIG. 1; and,

FIG. 7 is a bottom plan view of the bottle with nipple of FIG. 1.

The broken lines appearing in the drawings are for the purpose of illustrating portions of the article in which the design is embodied. Portions of the article appearing in broken lines form no part of the claimed design.
